UNITED STATES PATENT OFFICE.

FRANK M. SNYDER, OF LA FAYETTE, INDIANA, ASSIGNOR TO PEERLESS WIRE GOODS COMPANY, OF LA FAYETTE, INDIANA, A CORPORATION OF INDIANA.

BASKET FOOT.

Application filed April 8, 1925. Serial No. 21,479.

To all whom it may concern:

Be it known that I, FRANK M. SNYDER, a citizen of the United States, residing at La Fayette, in the county of Tippecanoe and State of Indiana, have invented a new and useful Basket Foot, of which the following is a specification.

My invention relates to improvements in foot members for mesh wire baskets and is particularly adapted for use on the wire mesh baskets of the larger type which are capable of carrying comparatively heavy loads and are intended more particularly to be slid over the floors.

One of the objects of my invention is to provide a foot member which, when secured in position to the bottom of the basket will permit the basket to be readily slid over the floor without damage to the floor.

For the purpose of disclosing my invention I have illustrated one embodiment thereof in the accompanying drawings in which,

Fig. 1 is a perspective of a wire basket having a plurality of foot members attached thereto;

Fig. 2 is a bottom plan of one corner of a basket showing more particularly the foot member and the manner of attachment;

Fig. 3 is an end elevation of so much of a basket as is necessary for the purpose of illustrating the foot member, and

Fig. 4 is a sectional view on the line 4—4 of Fig. 2.

In the embodiment of the invention the basket 1 is preferably provided with foot members 2 each of which is of the construction shown more particularly in Figs. 2 to 4. Each of the members 2 preferably comprises a bottom plate 3 preferably rectangular in form and sufficiently wide to bear upon a plurality of the wire strands 4 in both directions. In the particular structure illus-

trated the foot plate 3 is preferably sufficiently wide in both directions to bear upon at least three strands. The center of the plate is preferably struck up to form a semi-spherical dome 5 which, however, is preferably flattened as at 6 at its top and perforated as at 7.

The plate member 3 is secured in position on the under side of the bottom of the basket by means of a clamping plate 8 which has a down-turned flange cut away at the points 9 and 10 to accommodate the wire meshes and thereby form a plurality of fingers 11 which are turned in over the plate 3, thereby securely clamping the plate in position.

The opening 7 provides an escape for any moisture or water which may drain into the cup during the washing of the basket and also permits the draining of the tin when the entire basket, together with its foot plates, is emersed in a tinning bath. Without the opening this hollow dome would fill with tin thereby materially increasing the weight of the basket and adding to the cost of the basket.

I claim as my invention:

A foot member for wire mesh baskets comprising a bottom plate having struck up therefrom a hollow dome-like portion and arranged to be mounted on the under face of the bottom of the basket and a clamping plate for said bottom plate comprising a plate arranged to be mounted on the opposite face of the bottom of the basket and provided with an annular lip arranged to engage over the bottom plate, said lip being cut away at predetermined points to accommodate the wire meshes of the basket.

In witness whereof, I FRANK M. SNYDER have hereunto set my hand at La Fayette, Indiana, this third day of April, A. D. one thousand nine hundred and twenty-five.

FRANK M. SNYDER.
